UNITED STATES PATENT OFFICE

ANDREW OLSON AND WALTER HOLMS, OF CLEVELAND, OHIO, ASSIGNEES, BY MESNE ASSIGNMENTS, TO THE CLEVELAND FOLDING MACHINE COMPANY, A CORPORATION OF OHIO (1929)

MOVING DEFLECTOR

Application filed November 23, 1928. Serial No. 321,369.

This invention relates to improvements in moving deflectors for use upon paper handling machines and has particular utility when employed in connection with paper 5 folding machines designed to handle sheets printed with two or more signatures that are cut apart during the travel of the sheet through the folding machine, the corresponding signatures from all of the sheets being 10 delivered and stacked separately.

One of the objects of the invention is the provision of a deflector of this type which shall be simple in construction and certain in its operation.

15 Another object is the provision of means for actuating the sheet deflector, said means comprising shoes in the different courses taken by the signatures, said shoes being shifted by the travel of the signatures themselves, together with means for transmitting motion from one shoe to the other, whereby one shoe is always in operative position, the deflector itself comprising a portion of said last-named means.

25 Other objects and features of novelty will appear as we proceed with the description of that embodiment of the invention which, for the purposes of the present application, we have illustrated in the accompanying drawings, in which

Fig. 1 is a side elevational view of a fragment of a sheet stacker embodying our invention;

35 Fig. 2 is a plan view partially in section on line 2—2 of Fig. 1;

Fig. 3 is a detail sectional view on line 3—3 of Fig. 1;

40 Fig. 4 is a longitudinal vertical sectional view taken substantially on line 4—5 of Fig. 2, and showing the deflector in position to direct sheets onto the upper stacker belt; and

Fig. 5 is a view similar to Fig. 4 but with the deflector in position to direct sheets onto the lower stacker belt.

45 In the drawings we have shown at 10 a fragment of the frame of a folding machine. On this frame are rotatably mounted delivery rolls 11 and 12 connected for rotation by intermeshing gears 13 and 14, one of these gears 50 being driven in some suitable manner from

other moving parts of the folding machine.

Folded sheets delivered by the rolls 11, 12 ride over a guide plate 15 and are thereby directed between feed rolls 16 and 17 of the stacker, these rolls being mounted for rotation in the side members 18 of the stacker frame. The rolls 16 and 17 are mounted upon shafts 19 and 20, respectively, which extend through both of the frame members 18. On the forward side of the machine these shafts 60 carry intermeshing gears 21 and 22. The latter gear meshes with an idler 23 rotatably supported upon the forward frame member 18. When the stacker is set in operative position, with respect to the folding machine, the 65 idler 23 is caused to mesh with a gear 24 mounted on the shaft of roll 12 behind the frame member 10 of the folding machine. By this means driving force is transmitted from the machine to the stacker.

70 Behind the rolls 16, 17, that is speaking with regard to the line of travel of the sheets through the machine, and in the path of the sheets delivered by the rolls 16, 17, there is a shaft 25 upon which is fixed a deflector 26 triangular in cross section. The forward edge or nose of the deflector is shiftable across the path of the sheets from one side to the other thereof, these positions being indicated in Figs. 4 and 5. Outside the forward frame 75 member 18 the shaft 25 is slotted to take a small plate 27 that extends radially beyond the shaft for an appreciable distance, forming projections. This plate may be pinned or otherwise held in place in the shaft and, 80 obviously, the projections on the shaft may be otherwise formed, if desired.

85 The folded sheets, deflected either up or down by the deflector 26, are directed by the flat sides of the deflector into two different courses, one between the rolls 28 and 29 and the other between the rolls 30 and 31. The rolls 29 and 31 are preferably cylindrical metal rolls provided intermediate their ends with annular recesses 32 and 33. The rolls 90 28 and 30, however, are similar to the rolls 11, 12, 16 and 17, having spaced apart paper contacting disks or wheels. The shafts upon which the rolls 28, 29, 30 and 31 are mounted 95 extend through the rear frame member 18 of 100

the machine, and are there furnished with intermeshing gears 34, 35, 36 and 37, respectively, the gear 34 meshing in turn with an idler gear 38 rotated by a gear 39 on the rear end of the shaft 19.

5 Rock shafts 40 and 41 are supported in bearings in the frame members 18 above and below the deflector 26. Intermediate their ends and at points opposite the annular recesses 32 and 33 in the rolls 29 and 31, these shafts carry shoes 42 and 43 which preferably have counterbalancing arms 44 and 45, respectively. The free ends of these shoes are adapted to extend into the annular recesses 32 and 33, as indicated for the shoe 42 in Fig. 4 and the shoe 43 in Fig. 5, or to be shifted out of said recesses and to extend into the spaces between the disks or wheels of the adjacent rolls 28 and 30, as indicated 10 for the shoe 43 of Fig. 4 and the shoe 42 of Fig. 5. When a folded sheet traveling over the surface of one of the rolls 29 or 31 encounters a shoe extending into the recess 32 or 33, as the case may be, the shoe is immediately swung upon its axis, moving out of the recess and thereafter riding over the sheet in the case of the shoe 42, or under it in the case of the shoe 43.

15 The shafts 40 and 41, on their forward extremities, have secured thereto crank fingers 46 and 47, the outer ends of which bear against the plate 27 on opposite sides of the shaft 25. Hence, whenever the shafts 40 or 41 turn in response to the swinging of 20 the shoes 42 or 43 motion is transmitted to the shaft 25 through the intermediacy of the plate 27, and the deflector 26 is thus shifted from one operative position to the other.

25 At the same time, the swinging of one of the shoes 42 or 43 out of the corresponding recess 32 or 33, caused by the travel of the folded sheet over the recess, serves to transmit motion through the two crank fingers 46 and 47 and the intervening plate 27 to the 30 other shoe, bringing the free end of the latter back into its annular recess, in other words setting it in operative position.

35 Folded sheets leaving the rolls 28, 29 drop onto an endless stacker belt 48 which is continuously moved at relatively slow speed by any suitable means, such, for instance, as a train of gears comprising the gear 35, an idler gear 49 and a gear 50 mounted on a roller 51 over which the belt runs, this train 40 of gears being located behind the rear frame member 18 of the machine. Folded sheets delivered from the rolls 30, 31 drop onto a stacker belt 52 which runs over a roller 53 carrying at its rear end a gear 54 which 45 meshes with an idler 55 driven by the gear 37.

50 Starting with the position of the parts illustrated in Fig. 4, a sheet of paper traveling over the plate 15 and through the feed rolls 16 and 17 emerges therefrom and strikes 55 upon the upper surface of the deflector 26

and is thereby guided upwardly between the rolls 28 and 29. In order that the forward edge of the sheet may pass through these rolls, however, it must first push aside the free end of shoe 42, that is it must shift the 70 shoe out of the recess 32 and into the position illustrated in Fig. 5. The amount of force necessary to swing the shoe to this extent is readily exerted by the advancing folded sheet. At the same time the crank 75 46 is also swung through a corresponding angle to the position illustrated in Fig. 5, and the nose of the deflector is thereby shifted from the position of Fig. 4 to that of Fig. 5. This is ordinarily done before the rear edge of the sheet has passed the nose of the deflector. When the deflector is thus moved, the plate 27 swings the crank 47 from the position of Fig. 4 to that of Fig. 5, and this movement acting through the shaft 41 swings the shoe 43 from its inoperative position of Fig. 4 into its operative 80 position of Fig. 5. The next succeeding sheet traveling through the rolls 16 and 17 therefore engages the under side of the deflector 26 and has its course bent downwardly so that the sheet passes between rolls 30 and 31, engaging the shoe 43 and swinging it from the position of Fig. 5 back to the position of Fig. 4, thereby shifting the deflector 26 again back to its original position of Fig. 4, and resetting the shoe 42 into its operative 85 position of Fig. 4. The cycle of operations thereafter repeats itself.

90 The deflector 26, it will be observed, is shifted by the movement of the sheets themselves, and is always in proper position regardless of the time interval between succeeding sheets.

95 In Figs. 4 and 5, the two positions of the folded sheets, corresponding to the positions of the deflector parts illustrated in the respective figures is shown in full lines. The later position of one of the sheets, after it has travelled through the deflecting mechanism, is indicated in the same figures in dotted lines.

100 Although in the present disclosure we have illustrated and described with considerable particularity one preferred embodiment of the invention, we desire it to be understood that such detail disclosure is primarily for purposes of illustration and is not to be construed as limiting the scope of the invention.

105 Having thus described our invention, we claim:

110 1. In a paper handling machine, means for causing the sheets to travel single file in a given path, a deflector for directing sheets 115 from said path into either of two different courses, a shoe in each of said courses adapted to be shifted by the sheets traveling therethrough, and a connection between said deflector and each of said shoes, whereby the 120

- movement of one shoe out of operative position due to the travel of a sheet in the corresponding course sets the deflector to direct the succeeding sheet into the other course, and the movement of the deflector sets the other shoe into operative position. 5
2. In a paper handling machine, means for causing the sheets to travel single file in a given path, a deflector for directing sheets from said path into either of two different courses, a shoe in each of said courses adapted to be shifted by the sheets traveling therethrough, and means comprising the deflector itself for operatively connecting said two shoes, whereby the travel of a sheet in one of said courses shifts the deflector to direct a succeeding sheet into the other course and shifts the other shoe into operative position. 10
3. In a paper handling machine, means for causing sheets to travel single file in a given path, a pivoted deflector for directing sheets from said path into either of two different courses, a shoe in each of said courses adapted to be shifted from operative to inoperative position by a sheet traveling that course, means for operatively connecting said two shoes, whereby the movement of one shoe into inoperative position due to the travel of a sheet in that course shifts the other shoe into operative position, said means comprising two articulated connections, one between each of said shoes and said deflector, whereby the deflector is shifted from one operative position to the other when either of said shoes is shifted by the travel of a sheet in its course. 20
4. In a paper handling machine, means for causing sheets to travel single file in a given path, a pivoted deflector for directing sheets from said path into either of two different courses, a shoe in each of said courses adapted to be shifted from operative to inoperative position by a sheet traveling that course, a crank operatively associated with each of said shoes bearing at its outer extremity against said deflector at a point removed from the axis thereof, said cranks working in opposition upon said deflector, whereby the movement of either shoe out of operative position by the travel of a sheet in its course shifts the deflector to direct a succeeding sheet into the other course and moves the other shoe into operative position. 40
5. In a paper handling machine, means for causing sheets to travel single file in a given path, a pivoted deflector for directing sheets from said path into either of two different courses, a shoe in each of said courses adapted to be shifted from operative to inoperative position by a sheet traveling that course, a pair of projections extending outwardly from said deflector at one end thereof, a crank operatively associated with each of said shoes and bearing at its outer extremity against one of said projections, the movement of one of said shoes to inoperative position by the travel of a sheet acting through the corresponding crank and projection to shift said deflector in one direction and a similar movement of the other shoe acting to shift the deflector in the opposite direction, said deflector serving through the connections stated to transmit movement from one shoe to the other. 50
6. In a paper handling machine, means for causing sheets to travel single file in a given path, a pivoted deflector for directing sheets from said path into either of two different courses, a pair of pivoted shoes, each extending at times into one of said courses and adapted to be swung away from said course by the travel of a sheet therethrough, a crank attached to the pivot of each of said shoes, and a pair of opposed outwardly extending projections upon said deflector with which the free ends of said cranks engage, whereby the movement of one shoe out of the corresponding course is communicated to said deflector to swing the same, and through said deflector to the other crank to swing the other shoe into its course. 60

In testimony whereof, we hereunto affix our signatures.

ANDREW OLSON.
WALTER HOLMS.
